UNITED STATES PATENT OFFICE

WILLIAM R. YOUNG, OF FAIRFIELD, CONNECTICUT

DESIGN FOR A LAMP

Application filed August 25, 1932. Serial No. 44,691. Term of patent 3½ years.

To all whom it may concern:

Be it known that I, WILLIAM R. YOUNG, a citizen of the United States, residing at Fairfield, county of Fairfield, and State of Connecticut, have invented a new, original, and ornamental Design for Lamps, of which the following is a specification, reference being had to the accompanying drawing, forming part thereof.

The birds represented in the drawing are flat, and are shown with extended wings in the act of flying and are preferably cast from bronze or other suitable material, although

they may be cast so as to have a natural thickness, if desired.

The shape of the base is immaterial, but in the present instance it is rectangular and has rounded corners.

The figure is an elevation of the article showing my new design.

I claim:

The ornamental design for a lamp as shown and described.

In testimony whereof I affix my signature hereto.

WILLIAM R. YOUNG,
